[57] CLAIM

The ornamental design for a combined insulated container and collapsible grill, as shown.

DESCRIPTION

FIG. 1 is a top, front and side perspective view of a combined insulated container and collapsible grill showing my new design;

FIG. 2 is a side elevational view thereof;

FIG. 3 is a front elevational view thereof;

FIG. 4 is a top plan view thereof;

FIG. 5 is a bottom plan view thereof;

FIG. 6 is a rear elevational view thereof; and

FIG. 7 is a perspective view thereof in an open position.

FIG-1-FIG-2-FIG-3-7-7-4-7-7-5-7-7-6-7-7-7
